CABLE TENSION INDICATOR

Clifford E. Cushman, Burbank, Calif., assignor to
Sturgess, Inc., Glendale, Calif., a corporation
of California

Application July 16, 1946, Serial No. 131,615

Term of patent 14 years

(Cl. D52—1)

To all whom it may concern:

Be it known that I, Clifford E. Cushman, a citizen of the United States, and a resident of the city of Burbank, county of Los Angeles, State of California, have invented a new, original, and ornamental Design for a Cable Tension Indicator, of which the following is a specification, reference being had to the accompanying drawing, forming a part thereof.

Fig. 1 is a front and side perspective view of a cable tension indicator, showing my new design.

Fig. 2 is an elevation showing the rear side of the cable tension indicator.

Fig. 3 is a left side view of the device shown in Fig. 1 of the drawing.

I claim:

The ornamental design for a cable tension indicator, substantially as shown.

CLIFFORD E. CUSHMAN.
